UNITED STATES PATENT OFFICE.

GARFIELD A. WOOD, OF DETROIT, MICHIGAN.

HOISTING MECHANISM FOR MOTOR-VEHICLES.

1,271,971.

Specification of Letters Patent. Patented July 9, 1918.

Application filed August 28, 1916. Serial No. 117,236.

To all whom it may concern:

Be it known that I, GARFIELD A. Wood, a citizen of the United States, residing at Detroit, in the county of Wayne and State 5 of Michigan, have invented a new and useful Hoisting Mechanism for Motor-Vehicles, of which the following is a specification.

It is common practice to dump the contents of truck bodies by lifting the front 10 end upwardly about pivots at the rear end of the chassis, and hydraulic hoisting means has been used for this purpose. The most convenient source from which to operate the hoisting means is the propeller shaft (ordinarily arranged longitudinally of the vehicle); but, on account of the fact that the heavy loads and shocks incident to hoisting are borne on the side frame and independently of the propeller shaft, the deflection 15 of the former is not transmitted to the latter. Again, it is desirable to provide for slight inaccuracies in the construction of either hoisting means or chassis (often made by different manufacturers), whereby assembling of the parts is facilitated. It is further desirable to avoid the liability of leakage which results from independently supporting the pumping and hoisting elements of which the hoisting means as a 20 whole is made up, and to provide for convenient control of the mechanism by the driver of the vehicle. With these ends in view, the present invention consists in means for so connecting the pump driving means 25 to the power shaft as to allow the parts to be readily assembled and to be thereafter operated without in any way tending to bend the propeller shaft; in a unitary pump and hoisting cylinder mounted on a supplementary frame which is itself carried by 30 the chassis; and in control mechanism also carried by the unitary pump and hoisting cylinder whereby the several operations incident to the use thereof may be readily controlled by the driver. It also consists in the 35 details of construction shown, described and particularly pointed out in the claims.

Certain general combinations of elements and certain specific features relevant to the 40 construction of the mechanism shown and claimed herein are claimed in my earlier co-pending applications for U. S. Letters Patent, namely:

S. N. 183,979, filed August 1, 1917, (re- 45 newal of S. N. 14,480, filed March 15, 1915)

and the division thereof S. N. 115,957, filed Aug. 21, 1916;

S. N. 14,479, filed March 15, 1915, and the division thereof S. N. 117,235, filed Aug. 28, 1916.

60

In the drawings, Figure 1 is a fragmentary side view of a motor truck showing a preferred embodiment of my invention. Fig. 2 is a front elevation corresponding to Fig. 1, parts being omitted. Fig. 3 is an 65 enlarged view on the line 3-3 of Fig. 1. Fig. 4 is a part-elevation part-central vertical section corresponding to Fig. 3. Fig. 5 is a section on the line 5-5 of Fig. 4. Fig. 6 is a plan view of the clutch mechanism, parts being broken away. Fig. 7 is a section on the line 7-7 of Fig. 6. Fig. 8 is a fragmentary end view showing a modification. Fig. 9 is a fragmentary side view corresponding to Fig. 8, parts being broken 70 away. Fig. 10 is a section on the line 10-10 of Fig. 9. Fig. 11 is a plan view of one member of the clutch.

Similar reference characters refer to like parts throughout the several views.

80

Referring to the embodiment of my invention shown in Figs. 1 to 7, inclusive, 1 indicates the side frames of the vehicle to the rear end of which are secured brackets 2 bearing pivots 3 about which the body 4 85 may be swung vertically for dumping purposes. The body may include the longitudinal frame pieces 5 so arranged as to rest, when in lowered position, either on the side frames 1 or on special chairs carried thereby 90 (not shown). This general construction is well known.

The side frames may be cut away at a point 6 forward of the front end of the body, and may there support the cross bars 8 95 (preferably angle-irons having their horizontal flanges facing each other) upon which rests the flanged base 9 of a hoisting cylinder 10, the piston rod 11 of which, through cross bar 12, sheaves 13, cables 14 100 (shown in dashed lines in Fig. 1), equalizing bar 15, shackle 16 (omitted in Fig. 1) and brackets 17 secured to the body, serves to elevate the front end of the latter. The cylinder has secured to its upper end a 105 chamber or tank 19 that may be in free communication with the interior of the cylinder above the piston, whereby storage space for liquid is formed.

Attached to the base 9 by bolts 21 is a 110

gear pump 22 containing the driven gear 23 and the annular driving gear 24, the latter being keyed on a sleeve 25 rotatable in roller bearings 26 that turn in the threaded hubs 28 integral with the pump casing. The joints between the hubs and the sleeve may be sealed by the packing 29 and packing nuts 30, and in order to allow the rollers to be assembled, a retaining ring 31 may be 5 threaded into each of the hubs. Passing through the sleeve is the usual propeller shaft 34, and it will be seen that the relative dimensions of the parts is such as to allow considerable deflection of the side frames 10 and hoisting cylinder without bringing the sleeve into bearing engagement with the shaft.

The latter has rigidly secured thereto a clutch member that may be formed of the duplicate clamp sections 35 secured together by bolts 36. Slidably mounted upon the sleeve is a clutch shifting member 38, grooved at 39 to receive the yoke blocks 40 into which are threaded the bolts 41 that 15 also pass through the ends of the levers 42. The latter are secured to a shaft 43 that is mounted in the ears 44, rigid with the pump casing, and may be swung about the axis of the shaft by an arm 45 and a link 46 pivoted 20 at 47 to a lever 48 that, in turn, is pivoted to the tank 19 at 49. Projecting from the member 38 at each side is an ear 50 (Fig. 6) through which passes a bolt 51 that is 25 threaded therein; reduced portions of these bolts also extend through an annular clutch ring 52 and have reduced inner ends 53 that slide longitudinally in slots 54 formed in the sleeve 25. Thus the sleeve, the member 38 and the clutch ring are constrained to rotate 30 together, while the two last mentioned members are slidable on the sleeve. The clutch ring is slidable radially of the propeller shaft on the pins or bolts 51 to automatically 35 compensate in one direction for lack of alignment between the propeller shaft and the sleeve. Lack of alignment in a direction at right angles to that first mentioned is provided for by slippage of the clutch members 35 on teeth 55 that project from the 40 ring 52, and overlap the members 35 when thrust to the left (Fig. 6). Consequently, 45 rotation of the shaft may be transmitted undiminished to the sleeve even though their axes are not coincident and regardless of the 50 fact that considerable deflection of the sleeve 55 may take place when lifting heavy loads.

As stated previously, the tank 19 constitutes a storage receptacle for liquid (preferably oil) and communication is established 50 between the tank and intake passage 58 of the pump (Fig. 5) by a pipe 59 and fitting 60, and is expelled from the gears through the discharge passage 60', that may be brought into connection with the space between 65 the lower end of the cylinder and the

piston (not shown) by a three-way valve 61 and passage 62 (Fig. 5). Another passage 63 leads from the intake to the passage 62, and, when the valve is in the position shown, the liquid by-passes the gears and the piston 70 sinks. Various other arrangements of passages for the liquid may, of course, be used, but that described is preferred since, besides the advantages already stated, the liquid may be circulated continuously within 75 the pump itself by turning the valve so as to close the passage 62, which avoids starting and stopping of the engine. The valve may be operated by means of the lever 64, link 65 and lever 66, and the throw of both 80 the lever 66 and the lever 48 may be limited by the stop 67 that projects from the tank 19.

Instead of locating the pump so that the propeller shaft passes through the driving gear, a similar pump 68 having gears that 85 correspond in function to the gears 23 and 24 may be mounted on the cross bars 8 as indicated in Fig. 8. In this instance the liquid is drawn from the tank through the pipe 69 and discharged through the pipe 70 90 into the space beneath the piston, as before. The shaft of the driving gear, that is, the gear which corresponds to the gear 24, however, is driven by a sprocket gear 71 and chain 72 from a second sprocket gear 73 95 rigid with a sleeve 74, and the latter is rotatably mounted in a split bracket 75 secured to one of the cross bars. Longitudinal movement of the sleeve in respect to the bracket is prevented by the flanges 76 and 100 77. It will be noted that the inner diameter of the sleeve is considerably greater than the exterior diameter of the propeller shaft 34, and that the latter passes through it as before. Slidable longitudinally through 105 opposed openings in the sleeve are the clutch pins 78, rigid with a yoke collar 79 having a circumferential groove 80 into which pins 81 project. These pins, as before, are carried by arms 82 rigid with a shaft 83, rotatable in ears 84 that are attached to the bracket 75, and a lever 85 and link 86 constitute means for shifting the collar and pins in respect to the sleeve. When the pins are thrust to the right (Fig. 9) they 110 engage with teeth 88 on a floating ring 90 drilled to receive pins 91 on the arms 92 of a two-part member 93 that is clamped to the propeller shaft by bolts 94. In order to prevent the ring 90 from shifting transversely on the pins 91 when the clutch members are not engaged, opposed springs 95 are inserted between the arms 92 and the ring 90.

It will be observed that in both modifications the bars 8 constitute a frame (supplementary to that of the chassis and resting thereon) on which is directly carried a unit which comprises both the hoisting cylinder and the gear pump. This construction is of 125

much importance for the reason that, were the gear pump mounted directly on the chassis or on the engine, the heavy shocks and loads to which the cylinder is subjected and 5 the extremely high liquid pressures which are necessarily employed would cause relative deflections such as would render it practically impossible to maintain tight joints. Again, the construction, being itself assembled and including all necessary parts, is 10 readily assembled on and accommodates itself without alteration to slight variations in the chassis. Its control levers are located at a point where they are accessible to the 15 driver and yet do not interfere with the other control mechanism by which the adjacent foot space is ordinarily substantially filled.

Obviously, the details of the various parts 20 may be changed without departing from the spirit of my invention. I do not, therefore, wish to be limited otherwise than as indicated by the subjoined claims.

I claim:—

25 1. In combination with the frame and a rotatable shaft of a motor vehicle, a hoisting device supported by the frame, and clutch mechanism for actuating the hoisting device from the shaft, part of said clutch mechanism being carried by the shaft and another part being supported independently thereof, one of the parts being capable of bodily movement transversely of the shaft, whereby 30 considerable deflection of the frame in respect to the shaft may take place without inducing bending stresses in the shaft, and a manually operated lever for shifting an element of one of said clutch mechanism parts to or from driving engagement with an element of the other clutch mechanism part at 35 will.

2. In combination with the frame and a rotatable shaft of a motor vehicle, a driven mechanism supported by the frame, and 45 clutch means for actuating the driven mechanism from the shaft, said clutch means including an element fixed to the shaft to rotate therewith, a clutch ring supported by said element and movable bodily transversely of the shaft, said clutch means including a tubular member spaced from and surrounding the shaft, said member being supported independently of the shaft, and manually controllable means shiftable at 50 will in respect to the tubular member through which force for driving the tubular member from the clutch ring is transmitted when said shiftable means is in one position.

3. In combination with the frame and a 55 rotatable shaft of a motor vehicle, a driven mechanism supported by the frame, a clutch member rotatable with the shaft, a rotatable member supported by the frame and extending around said shaft and spaced therefrom, 60 a pin slidable through the rotatable mem-

ber into and from the path of the clutch member.

4. In combination with the frame and a rotatable shaft of a motor vehicle, a hoisting device supported by the frame, and clutch mechanism for actuating the hoisting device from the shaft, part of the clutch mechanism being carried by the shaft and another part being supported independently thereof, said rotatable shaft passing through said last 70 mentioned part of the clutch mechanism, one of the parts of the clutch mechanism being capable of movement transversely of the shaft whereby deflection of the frame in respect to the shaft, due to loads on the hoisting device, may take place without inducing 75 transverse bending stresses in the shaft.

5. In combination with the frame and a rotatable shaft of a motor vehicle, a hoisting device supported by the frame, and clutch mechanism for actuating the hoisting device from the shaft, part of the clutch mechanism being carried by the shaft and another part being supported independently thereof, one of the parts being capable of 80 movement transversely of the shaft, whereby deflection of the frame in respect to the shaft, due to loads on the hoisting device, may take place without inducing transverse bending stresses in the shaft, one of the 85 clutch parts being movable longitudinally of the shaft to engage with or disengage from the other parts whereby rotative movement of the shaft is made to cause rotative movement of the clutch part that is supported independently of the shaft.

6. In combination with the frame and a rotatable shaft of a motor vehicle, a hoisting device supported by the frame, and clutch mechanism for actuating the hoisting device from the shaft, part of the clutch mechanism being carried by the shaft and another part being supported independently thereof, said rotatable shaft passing through said last 105 mentioned part and being spaced therefrom, one of the parts being capable of movement transversely of the shaft, whereby deflection of the frame in respect to the shaft, due to loads on the hoisting device, may take place without inducing transverse bending stresses 110 in the shaft, one of the clutch parts being movable longitudinally of the shaft to engage with or disengage from the other part whereby rotative movement of the shaft is made to cause rotative movement of the 115 clutch part that is supported independently of the shaft.

7. In combination with the frame and a rotatable shaft of a motor vehicle, a hoisting device supported by the frame, and mechanism for actuating the hoisting device from the shaft, said mechanism including a sleeve supported by the frame and through which the shaft passes, said shaft being spaced 125 from the sleeve, a clutch member secured to 130

the shaft, a second clutch member carried by the sleeve, said second clutch member also being spaced from the shaft, whereby deflection of the sleeve in respect to the shaft may 5 take place without inducing bending stresses in the shaft.

8. In combination with the frame and a rotatable shaft of a motor vehicle, a hoisting device supported by the frame, and mechanism for actuating the hoisting device from the shaft, said mechanism including a sleeve supported by the frame and through which the shaft passes, said shaft being spaced from the sleeve, a clutch member secured to the shaft, a second clutch member carried by the sleeve, said second clutch member also being spaced from the shaft, whereby deflection of the sleeve in respect to the shaft may take place without 15 inducing bending stresses in the shaft, one of the clutch members being movable longitudinally of the shaft to be engaged with or disengaged from the other clutch member at will.

25 9. In combination with the frame and a rotatable shaft of a motor vehicle, a hoisting device supported by the frame, and mechanism for actuating the hoisting device from the shaft, said mechanism including a sleeve supported by the frame and through which the shaft passes, said shaft being spaced from the sleeve, a clutch member secured to the shaft, a second clutch member carried by the sleeve, means for preventing rotative 30 movement and for allowing longitudinal movement of the second clutch member in respect to the sleeve to thus engage with or disengage from the first mentioned clutch member, said second clutch member also 35 being spaced from the shaft, whereby deflection of the sleeve in respect to the shaft may take place without inducing bending stresses in the shaft.

40 10. In combination with the frame and a rotatable shaft of a motor vehicle, a hoisting device supported by the frame, and mechanism for actuating the hoisting device from the shaft, said mechanism including a sleeve supported by the frame and through which the shaft passes, said shaft being spaced from the sleeve, a clutch member secured to the shaft, a second clutch member carried by the sleeve, means for preventing rotative 45 movement and for allowing longitudinal movement of the second clutch member in respect to the sleeve, means in respect to which the sleeve and second clutch member are rotatable, for moving the second clutch member longitudinally of the shaft to engage with or disengage from the first mentioned clutch member at will, said clutch member also being spaced from the shaft, whereby deflection of the sleeve in respect to the shaft may take place without inducing 50 bending stresses in the shaft.

11. In combination with the frame and a rotatable shaft of a motor vehicle, a hoisting device supported by the frame, and mechanism for actuating the hoisting device from the shaft, said mechanism including a rotatable member supported by the frame and through which the shaft passes, said shaft being spaced from the rotatable member, a clutch member support secured to the shaft, a clutch member carried by the support, a second clutch member carried by the rotatable member, said second clutch member also being spaced from the shaft, whereby deflection of the rotatable member in respect to the shaft may take place without inducing bending stresses in the shaft, and means whereby the first clutch member is allowed limited movement transversely of the shaft.

12. In combination with the frame and a rotatable shaft of a motor vehicle, a driven mechanism supported on the frame, and clutch mechanism for actuating the driven mechanism from the shaft, part of the clutch mechanism being carried by the shaft and another part being supported independently thereof, one of the parts being capable of considerable bodily movement transversely of the shaft, said shaft passing through said last mentioned part and a manually actuated lever for connecting and disconnecting the parts of the clutch mechanism at will.

13. In combination with the frame of a motor vehicle and a driving shaft supported thereby, a clutch ring encircling the shaft and spaced therefrom, means carried by the shaft for supporting the clutch ring to swing about an axis at right angles to and substantially intersecting the axis of the shaft, said clutch ring having limited movement along the axis about which it is swingable, and manually actuated means spaced from the shaft and movable at will into and from engagement with the clutch ring at points spaced angularly considerably about the shaft from the ends of the axis about which the clutch ring swings, whereby the shaft may be caused to drive the manually actuable means at will.

14. In combination with the frame and a rotatable shaft of a motor vehicle, a driven mechanism supported by the frame, and clutch mechanism for actuating the driven mechanism from the shaft, said clutch mechanism including a part supported by the shaft, a second part rotatably supported independently of the shaft, and a third part including a plurality of pins supported in said second part and slidable in respect to said second part longitudinally of the shaft to and from engagement with the first mentioned part, said second part being spaced from said shaft, whereby relative movement of the second member and the shaft transversely of the axis of the latter is allowed.

15. In combination with the frame and

a rotatable shaft of a motor vehicle, a hoisting device supported by the frame, and mechanism for actuating said hoisting device, said mechanism including a hollow 5 sleeve carried by and rotatable in respect to said frame, said shaft passing through said sleeve, and being spaced therefrom, a member secured rigidly to the shaft, a floating clutch ring supported by said member, re- 10 silient means interposed between the member and the clutch ring, and a second clutch member rotatable with the sleeve and slide- 15 able longitudinally in respect to the shaft whereby it may be engaged with or disengaged from the floating clutch ring, the whole arrangement allowing deflection of the frame and sleeve without inducing trans- 20 verse bending stresses in the shaft.

16. In combination with the frame and 20 a rotatable shaft of a motor vehicle, a hoisting device supported thereon, and mechanism for actuating said hoisting device, said mechanism including a sprocket wheel having an open center through which the shaft 25 passes, said shaft being spaced from the sprocket wheel, a pump, a second sprocket wheel thereon, and a chain connecting the two sprocket wheels, means for driving said first sprocket wheel from said shaft, said 30 means allowing deflection of the sprocket wheel, due to loads on the hoisting device, without causing transverse bending stresses in the shaft.

17. In combination with the side bars and 35 a driven shaft of a motor vehicle, a supplemental support extending across between the side bars, a body tiltable on said truck, an upright hoisting cylinder supported on the supplemental support forward of the 40 front end of the body for tilting the body, means including a rotatable member supported on the supplemental support and spaced from and encircling said shaft, whereby liquid may be pumped to said cyl- 45 inder at will and whereby relative deflection of said support and shaft is allowed.

18. In combination with the frame and a 50 rotatable shaft of a motor vehicle, a hoisting device supported by the frame, and mechanism for actuating the hoisting device from the shaft, said mechanism includ- 55 ing a rotatable member supported by the frame independently of the shaft, said member extending around the shaft and be-

a pair of pins carried by said member and projectible therefrom, whereby the rotatable member may be connected to the shaft at will.

19. In combination with the frame and a 60 driven shaft of a motor vehicle, a clutch ring, means for supporting said ring to swing about an axis substantially intersecting the axis of the shaft and at right angles to the axis of said shaft, said ring having 65 clutch faces located in a plane at a large angle to the plane determined by the axis of the shaft and the axis about which the clutch ring swings, a rotatable driven element extending around the shaft and spaced 70 considerably therefrom, and a pair of pins projectible from said element into the path of the clutch faces at will.

20. In combination with the frame and a 75 shaft of a motor vehicle, a driven device on the vehicle, means for driving said device from the shaft, said means including an annular member through which the shaft passes, a clutch element slideable longitudinally of the shaft through which the annular member may be driven from the shaft at will, said annular member being spaced from the shaft to allow relative movement transversely of the axis of the shaft, means 80 for shifting the clutch element longitudinally of the shaft so constructed and arranged that the weight of the parts tends to hold said clutch element out of the position in which it transmits driving stress from 85 the shaft to the annular member.

21. In combination with a frame and a driven shaft of a motor vehicle, said frame and driven shaft constituting two elements, a clutch ring, means for supporting said ring on one of the elements to swing about 90 an axis at right angles to and substantially intersecting the axis of said shaft, said ring having clutch faces located in a plane at a large angle to that determined by the axis of the shaft and the axis about which the 95 ring swings, complementary clutch means carried by the other element, means for causing driving engagement between the clutch ring and the last mentioned clutch means at will, the parts being so constructed and arranged that the clutch ring and the complementary clutch means may have deflection relative to each other transversely of the shaft.

GARFIELD A. WOOD.
